PULL FOR A DRAWER

Anthony J. Carsello, Hollywood, Calif., assignor to Ajax Hardware Manufacturing Corp., City of Industry, Calif., a corporation of California

Original design application Sept. 25, 1964, Ser. No. 81,879.
Divided and this application May 20, 1965, Ser. No.
85,514

Term of patent 14 years

(Cl. D10—8)

FIG. 2.

FIG. 3.

FIG. 4.

FIG. 5.

FIG. 1 is an isometric view of a pull for a drawer, showing my new design;

FIG. 2 is a front elevational view;

FIG. 3 is a rear elevational view;

FIG. 4 is a top plan view; and

FIG. 5 is an end elevational view.

This application is a divisional application of Serial No. D. 81,879, filed September 25, 1964.

I claim:

The ornamental design for a pull for a drawer, as shown.
